PROCESS FOR UPGRADING ISOMERIZABLE HYDROCARBON COMPOUNDS

Norman L. Carr, Crystal Lake, Ill., assignor to The Pure Oil Company, Chicago, Ill., a corporation of Ohio

Filed Dec. 19, 1956, Ser. No. 629,318

9 Claims. (Cl. 208—66)

This invention relates to the production of high octane number motor fuels. It is more directly concerned with upgrading isomerizable hydrocarbon constituents boiling in the gasoline motor fuel range.

In a refining situation wherein such factors as high-cost crude petroleum oils and upward trends in the quality of gasoline type motor fuels are present, there are economic advantages in processing the normally gaseous hydrocarbons to produce liquid products and in upgrading the several liquid gasoline components which have low performance characteristics. Some light, gaseous ends can be converted to high octane number blending constituents by such processes as alkylation and polymerization. The octane ratings of the n-C₅—C₇ hydrocarbons in the gasoline range are best increased by isomerization. To effect this isomerization, there has been developed a number of processes which employ several types of catalysts. Earlier-developed processes, such as the Shell liquid phase isomerization process and the Isomate process of Standard Oil Co. (Ind.), employed AlCl₃-containing catalysts. It is preferable, however, to use non-corrosive, solid catalysts which can be more easily handled in this service. As a result, several processes, viz., Atlantic's Pentafining, and U.O.P.'s Penex, use a combination of platinum and silica-alumina or alumina to promote isomerization with low losses to fuel gas. These processes are effective for upgrading low-boiling petroleum distillates such as natural gasoline, 200° F. end-point virgin or cracked distillates, etc. While the n-pentane, and n-hexane constituents of these feed stocks are receptive to upgrading, the heptane fraction, in combination with these lighter hydrocarbons, is not effectively treated in processes employing platinum or palladium supported on a suitable catalytic support as the isomerization catalyst. To obtain maximum upgrading in the engine performance characteristics of low boiling petroleum distillates, consideration must therefore be given to the efficient processing of the normal, saturated paraffinic components which contain seven carbon atoms.

It is therefore a primary object of this invention to provide an integrated process for enhancing the octane number of n-heptane-containing, light petroleum distillates utilizing two reaction systems, each containing specific catalysts and operated under different conditions to effect quality enhancement. This and other objects will be apparent from the following detailed description of this invention.

The figure is a schematic flow diagram illustrating the split-treatment process of this invention.

There has been developed for use in isomerization processes of this nature a solid catalyst comprising a hydrogenation agent-cracking catalyst composite, e.g., Ni—SiO₂—Al₂O₃, I. and E. Chem., 45 (1), 147. It has further been found that the efficiency of catalysts of this kind can be substantially improved (Vide copending U.S. application of Norman L. Carr, viz., "Catalyst and Process," Serial Number 619,376, and filed October 31, 1956,

2

herewith) by preconditioning the catalyst in a certain prescribed manner, described in the aforementioned applications, prior to use. This technique, in essence, comprises incorporating a minor amount of a hydrogenation component in a refractory, mixed oxides base composited to evince acidic properties and hydrocarbon cracking activity substantially in accordance with conventional catalyst preparation techniques. The freshly prepared, "green" catalyst is activated in a reducing atmosphere in accordance with the prior art to effect reduction of the hydrogenation component of the catalyst as far as possible under specific conditions. Thereafter, the catalyst is subjected to the additional activation and conditioning treatment described in the above-mentioned applications.

In carrying out this preconditioning phase of the catalyst preparation, the composite catalyst is subjected to an oxidizing atmosphere maintained at a temperature of about 650° F. to 750° F. Following this oxidation, the oxidized catalyst is contacted with hydrogen at the same temperature as that at which the oxidation was carried out to reduce the reducible elements of the composition and produce a composite catalyst of high activity and resistance to degeneration.

It has been found that this composite catalyst effectively and efficiently upgrades n-heptane, a gasoline component having a zero octane rating, in addition to effectively upgrading n-pentane and n-hexane. Generally, n-heptane is present in isomerizable petroleum feed stocks in concentrations of about 10 to 15% by volume. When isomerizing a C₅—C₇ petroleum fraction in the presence of the above-described preconditioned catalyst composite, it has been found that pentane, hexane, and heptane each require different operating conditions for optimum conversion. It has also been found that these optimum conditions differ from those employed in processes utilizing platinum or palladium on silica-alumina or other similar acidic supports, especially with regard to temperatures, liquid volume hourly space velocities, and hydrogen/hydrocarbon mole ratios. Optimum pentane isomerization requires more severe conditions, i.e., higher temperatures, than do hexane or heptane, and, when isomerizing a C₅—C₇ fraction at high levels of pentane conversion, the requisite high temperatures decompose part of the heptanes, resulting in significant yield reduction through hydrocracking. To avoid this inimical result, it is necessary to compromise by balancing conversion against yield loss with an attendant loss in operating efficiency. According to this invention, this compromise can be avoided, and maximum operating efficiency maintained, by a split treatment of the C₅—C₇-containing feed stock, utilizing separate reaction systems. In this process, an isomerizable feed stock, containing C₅—C₇ hydrocarbons, is fractionated into a light fraction consisting essentially of pentanes and a heavier fraction containing normal C₆ and C₇ hydrocarbons. The light and heavy fractions are then isomerized separately under optimum isomerization conditions, employing different operating conditions, and different catalysts, in each reactor. A consolidated fractionation system performs the necessary feed preparation, product recovery, and recycle splitting. The basic concept of this invention may be broadened to cover a split treatment wherein a C₅—C₆ fraction is treated separately from a C₇ fraction or wherein the C₅, C₆ and C₇ fractions are all isomerized separately.

Referring to the flow diagram shown in Figure 1, feed stock, such as a stabilized natural gasoline or low-boiling petroleum naphtha containing C₅—C₇ hydrocarbons, is introduced into the consolidated fractionating system through line 10 and is depentanized in tower 11 after joining depropanized reaction effluent as discussed below. The overhead from tower 11, comprising isopen-

tane and normal pentane, passes through line 12 to deisopentanizer 13 wherein a fraction rich in isopentane is separated and sent to storage through line 14. A first feedstock, consisting essentially of normal pentane, is recovered as bottoms from deisopentanizer 13 and passed to heater 15 through line 16. Hydrogen-rich gas is introduced into line 16 through line 17 from a source which will hereinafter be discussed, forming a first reactor charge. This first reactor charge is heated to an elevated temperature and introduced into pentane reactor 18 through line 19 to provide a first reaction effluent which is processed as hereinafter described.

The bottoms from deisopentanizer tower 11 are transferred directly to deisohexanizer 20. The isohexane fraction is separated and passed overhead through line 14. The bottoms fraction from deisohexanizer 20 is transferred through line 21 to dehexanizer 22 from which overhead, comprising essentially pure hexane, is transferred through line 23 to a point of confluence with line 24 through which is being transferred the bottoms fraction, comprising normal heptane, from heptane tower 25. Bottoms from dehexanizer 22 are transferred to heptane tower 25 through line 26. Overhead from dehexanizer 22 and bottoms from heptane tower 25, after combining, are joined by hydrogen-rich recycle gas from line 27 to form a second reactor charge which passes through line 28, heater coil 29 and line 30 to one of alternative reactors 31 and 32.

Reaction effluent from pentane reactor 18, flowing through line 33, joins reaction effluent from hexane-heptane reactor 31 or 32, flowing through line 34 to form stream 35 which flows to separator 36. In separator 36, hydrogen-rich recycle gas is separated from the combined reactor effluents and is transferred through line 37 to branch lines 17 and 27 for combination with first and second reactor feeds flowing through lines 16 and 15, respectively.

Separated liquid from separator 36 flows through line 38 to depropanizer 39 wherein a propane and lighter fraction is separated for removal from the system through line 40. Depentanizer reaction effluent is withdrawn from depropanizer 39 through line 41 for combination

5 NiMoO₄ incorporated in a 50/50 silica-alumina carrier prepared in accordance with the copending application of Norman L. Carr, Serial Number 619,404, filed October 31, 1956, now U. S. Patent No. 2,917,566, granted December 15, 1959, entitled, "Catalyst and Process," and with a noble metal catalyst comprising 0.5 wt. percent platinum deposited on an alumina support were compared. This latter catalyst is a commercially available composition, and is prepared in accordance with prior art techniques. In Table I is summarized optimum yield per pass for individual hydrocarbon components obtainable when using the above base metal catalyst. For determining ultimate yield, it is assumed that perfect isomer fractionation and recovery are obtained with only the normal component being recycled for reprocessing.

TABLE I

Typical optimum yield per pass for individual components

[Isomerization over NiMoO₄—SiO₂—Al₂O₃ catalyst]

EXEMPLARY OPERATING CONDITIONS

Pressure, p.s.i.g.....	350
Liquid volume hourly space velocity.....	1.0
H ₂ /hydrocarbon mol ratio.....	3

Components (Feed)	Temperature, ° F.	Yield per pass, mol percent	Selectivity or Ultimate Yield, mol percent
Normal Pentane.....	740	44	72.0
Normal Hexane.....	710	68.2	91.5
Normal Heptane.....	670	67	84.0
Normal Octane.....	635	72.5	86.2
Methylecyclohexane.....	650-680	63	93.8

Using the foregoing preconditioned NiMoO₄-silica-alumina composite, a mixture of isomerizable hydrocarbons comprising 33.3 vol. percent n-pentane, 33.3 vol. percent n-hexane, and 33.3 vol. percent n-heptane was isomerized at a pressure of 350 p.s.i., a hydrogen/hydrocarbon mol ratio of 3, and a liquid volume hourly space velocity of 1 at several reaction temperatures. The results of these runs are tabulated in Table II. Similar results are obtained with other mixtures of C₅, C₆, and C₇ hydrocarbons.

TABLE II

Operation on mixed feed¹ (pentane, hexane and heptane)[NiMoO₄—SiO₂—Al₂O₃ Catalyst]

Temperature.....	660° F.				710° F.				
	Component In Feed	Isomer Yield per Pass, Mol Percent	Selectivity, Percent	Conversion, Mol Percent	Recycle-To Fresh Feed Ratio	Isomer Yield per Pass, Mol Percent	Selectivity, Percent	Conversion, Mol Percent	Recycle-To Fresh Feed Ratio
n-C ₅	12	86	14	6.1	37.1	85	43.6	1.3	
n-C ₆	52	97	53.6	0.87	68.5	91.5	74.9	0.34	
n-C ₇	66	87.5	75.4	0.33	61	65	94	0.06	
Average.....	43	90.2	-----	2.43	55.5	80.5	-----	0.57	

¹ Based on perfect isomer-normal separation and recycle of normal component only, selectivity is equivalent to ultimate isomer yield.

$$\text{Recycle to fresh feed ratio} = \frac{(1-x)}{x} = \frac{R}{F}$$

$$\text{Selectivity} = \frac{y}{x} = \text{ultimate yield}$$

R=recycle rate, pure reactant.

F=feed rate, pure reactant.

x=fractional conversion/pass.

y=fractional yield/pass.

with fresh feed entering through line 10 and ultimate separation of high octane isomeric constituents, which are removed through line 14 as product, and normal paraffinic constituents which are recycled to the pentane and hexane-heptane reactors.

In this investigation, results obtainable with a preconditioned isomerization catalyst comprising 10 wt. percent

70 From the results in Table II, it is seen that at an operating temperature conducive to the isomerization of the n-heptane constituent of the feed, and employing the exemplary operating conditions shown in Table I, the average isomer yield/pass is 43% with an ultimate yield average of 90.2% at an average recycle-to-fresh-feed ratio of 2.43. At the higher temperature, viz. 710° F.,

which is favorable to the isomerization of n-pentane and n-hexane it is noted that even though the isomer yield per pass is increased because of higher conversion, the ultimate yield of isomer has been deleteriously affected. The disadvantages of carrying out the isomerization using mixed feed stocks containing n-heptane is further illustrated in Table III wherein is shown that increased conversion and resulting yield are obtained in the processing of only n-pentane or n-hexane, per se, at these latter operating conditions.

TABLE III
Operation on normal pentane or normal hexane

Component	Isomer Yield, Mol Percent	Selectivity, Percent	Conversion, Mol Percent	Recycle-to-Fresh Feed Ratio
n-C ₅	40	85	47.1	1.12
n-C ₆	68	90	75.6	0.32

To illustrate the advantages of the instant invention, a feed stock was prepared to provide a low-boiling fraction consisting essentially of n-pentane and a high-boiling fraction consisting essentially of n-hexane and n-heptane.

In processing the high-boiling fraction at a temperature of 660° F., employing the exemplary operating conditions shown in Table I, the results summarized in Table IV are obtained.

TABLE IV
Operation on normal hexane-normal heptane mixture at 660° F.

Component	Isomer Yield, Mol Percent	Selectivity, Percent	Conversion, Mol Percent	Recycle-to-Fresh Feed Ratio
n-C ₆	52	97	53.6	0.87
n-C ₇	66	87.5	75.4	0.33
Average	59	92.3	64.5	0.60

The low-boiling, pentane-containing fraction was processed with the hereinbefore-described, platinum-containing catalyst. The results of processing this fraction are summarized in Table V.

TABLE V
Hydroisomerization of n-pentane over a platinum reforming catalyst

Temperature, °F	830
Pressure, p.s.i.g.	500

Conversion/pass, percent	55
Yield isopentane/pass, percent	52.7
Selectivity, percent	94

In contradistinction to the excellent results obtained in the isomerization of n-pentane, noble metal catalysts are not efficient for upgrading n-heptane fractions. Upon combining the liquid products obtained in these respective processes, a C₅+ blending stock is obtained having Research Octane Numbers of 74.8, without tetraethyllead, and 93.5 with 3 cc. of TEL/gal., on a naphthalene-free basis. With a typical naphtha feed containing naphthenes, these numbers are several units higher.

It is therefore apparent that the split-stream treatment of an isomerizable mixture containing C₅-C₇ hydrocarbons, comprising processing the n-pentane constituent at elevated temperatures and pressures favorable to the isomerization of pentane in the presence of a supported

platinum or palladium catalyst, and processing the higher-boiling constituents of the mixture at less severe isomerization reaction conditions in the presence of a pre-conditioned, acidic mixed oxides base-hydrogenation agent, composite isomerization catalyst, is superior to treatment of the entire C₅-C₇ fraction over either of these catalysts. Furthermore, the split treatment can be carried out with infrequent regeneration with sulfur-containing or sulfur-free feedstocks and low ratios of hydrogen. These features, in combination with the highly efficient hexane-heptane processing using the preconditioned base-metal catalyst, provide an operational scheme which is far superior to processing schemes using a full-boiling-range stock containing n-C₅-n-C₇ hydrocarbons as an isomerization feed. It is therefore evident that the split treatment of C₅-C₇-hydrocarbon-containing feed stocks in accordance with this invention has economic advantages in providing high pentane conversions and high overall yields of high octane products which can be used advantageously as blending stocks in gasoline formulations.

In the process of this invention the pentane isomerization catalyst comprises platinum or palladium supported on a cracking catalyst. Catalysts of the noble metal type, which are well known in the prior art and which are used in the pentane isomerization phase of this invention, contain about 0.01 to 1.0% by weight of platinum, or 0.5-2.0 weight percent of palladium on a cracking catalyst such as silica-alumina, silica-zirconia, silica-alumina-zirconia etc., or on activated alumina. Complete descriptions of such catalysts are contained in a number of U.S. patents such as 2,478,916; 2,479,109; 2,479,110; 2,589,189; 2,750,329; and others. Operating conditions for carrying out the pentane isomerization in the presence of a platinum- or palladium-containing catalyst are selected to attain optimum results. Accordingly, the following conditions are employed:

	Range	Preferred
Temperature, °F	830-900	850-875
Pressure, p.s.i.g.	200-500	350-500
Liquid Weight Hourly Space Velocity	2-10	2-4
H ₂ /Hydrocarbon mole ratio	0.1-0.5	0.25-0.5

The isomerization of the higher-boiling fraction of the feed stock, containing n-C₆ and n-C₇ hydrocarbons, is carried out in the presence of a preconditioned catalyst composite of improved efficiency prepared in accordance with copending U.S. application of N. L. Carr, entitled, "Catalyst and Process," Serial Number 619,376, filed October 31, 1956, now U.S. Patent No. 2,917,565, granted December 15, 1959. These catalysts are preconditioned in a certain prescribed manner described in the above-mentioned patent prior to use. As described above, this method of preparation involves preparing a composite catalyst comprising a minor amount of hydrogenation component incorporated in a refractory, mixed oxides base formulated to evince acidic properties and hydrocarbon cracking activity substantially in accordance with conventional catalyst preparation techniques. This catalyst is activated in accordance with the prior art to effect reduction of the hydrogenation component of the catalyst to its most reduced state under the conditions employed in the preparation. Subsequently, the composite catalyst is preconditioned by exposing it to an oxidizing atmosphere maintained at a temperature of about 650° F. to 750° F. Following this oxidation the oxidized catalyst is contacted with hydrogen at the same temperature as that at which the oxidation was carried out to reduce the reducible elements of the composition to their lowest state of valency and produce a composite catalyst of high activity and resistance to degeneration. Catalysts prepared in this manner are those which comprise a refrac-

7
tory, mixed oxides base composited to evince acidic properties and hydrocarbon cracking activity, having incorporated therein 2 to 10% of a hydrogenation component, such as group VIII metals of the iron period; oxides of polyvalent metals of groups V, VI and VII; and group VIII metal (of the iron period) salts of oxyacids of polyvalent metals of groups V, VI, and VII. Specific examples of these hydrogenation components include cobalt, nickel; tungsten oxide, molybdenum oxide, chromium oxide, manganese oxide, vanadium oxide; and cobalt and nickel salts of the oxyacids of tungsten, molybdenum, chromium, vanadium, and manganese, e.g., nickel tungstate, cobalt molybdate, nickel molybdate, etc. Suitable refractory, acidic, mixed oxide bases include but are not limited to SiO_2 — Al_2O_3 , SiO_2 — ZrO_2 , SiO_2 — TiO_2 , SiO_2 — B_2O_3 , Al_2O_3 — ZrO_2 , Al_2O_3 — BeO , Al_2O_3 — B_2O_3 , SiO_2 — CrO_3 , B_2O_3 — TiO_2 , SiO_2 — Al_2O_3 — ZrO_2 , SiO_2 — Al_2O_3 — BeO , and acid-treated clays. These mixed oxides, in forming the base, can be either in chemical or physical combination. From a standpoint of activity, it has been found that catalyst carriers containing 50 to 87% silica and 50 to 13% alumina, having incorporated therein 3 to 5% of the hydrogenation agent, are preferred. To facilitate the description of these catalysts they will be referred to as "preconditioned, refractory, acidic, mixed oxides base-hydrogenation agent composite isomerization catalysts" and so designated in the appended claims.

Operating conditions selected for the isomerization phase are those best suited for isomerization of normal pentane, hexane, and heptane. Accordingly, the following conditions are employed:

	Range	Preferred
Temperature, ° F.....	600-750	650-725
Pressure, p.s.i.g.....	180-1,000	350-750
Liquid Weight Hourly Space Velocity.....	0.1-2.0	0.5-1.5
H_2 /hydrocarbon mole ratio.....	0.1-4.5	0.5-3.5

Feed stocks which may be processed by the method of this invention include hydrocarbon mixtures containing saturated C_5 , C_6 , and C_7 paraffinic hydrocarbons. Suitable feeds include petroleum-derived, hydrocarbon mixtures, such as natural gasolines, naphtha distillates boiling up to about 210° F., light catalytic reformate, hydrogenated light coker naphtha, and others. Although it is preferable to stabilize the feed stock to remove the butane constituents, as is shown in the illustrated embodiment where they are removed in the deisopentizer, no operational difficulties arise if the butanes enter the reaction zone but they function as a diluent for the feed. Also the presence of naphthenes, while not desirable because they load the reactor with a component that is not upgraded in octane number, causes no trouble.

The foregoing specific description of the instant invention involves the prefractionation of a suitable hydrocarbon feed stock to produce a low boiling fraction consisting essentially of n-pentane and a consecutive, higher-boiling fraction containing n-hexane and n-heptane, and their subsequent respective isomerization under optimum catalytic conditions. It is to be understood, however, that other process variations can be utilized without departing from the essence of this invention. For example, the higher-boiling fraction can be further fractionated into a separate fraction consisting essentially of n-hexane and a separate fraction consisting essentially of n-heptane. The reaction system for processing this plurality of streams will still comprise the combination of catalysts described above except that a separate reactor containing "preconditioned, refractory, acidic, mixed oxides base-hydrogenation agent composite isomerization catalysts" will be employed for processing the n-hexane feed and n-heptane feed. A manipulative operation of this nature

will also require that the illustrated product recovery system be modified to permit the recycle of the n-paraffinic constituents of the reaction effluent to their respective reactors.

5 Because the n-hexane is receptive to being processed in the presence of the platinum or palladium catalysts or the "preconditioned, refractory, acidic, mixed oxides base-hydrogenation agent composite isomerization catalysts," it may be desirable to include this constituent in the low-boiling fraction. The adaptability of this component avoids the need for precise fractionators for exactly "splitting" the feed stock and permits the inclusion of this component in both the low-boiling n-pentane-containing fraction and the high-boiling n-heptane-containing fraction.

10 By employing the processing scheme of this invention, advantage is taken of the effectiveness of platinum- or palladium-containing catalysts for pentane isomerization at high space velocities. This permits relatively small amounts of catalysts to be required as compared with the amounts of "preconditioned, refractory, acidic, mixed oxides base-hydrogenation agent composite isomerization catalysts" required to attain the same severity of operation. On the other hand, these latter catalysts are especially effective for the isomerization of heptane, which is not as readily carried out in the presence of platinum or palladium catalysts. It is therefore apparent that the integrated, split-treatment isomerization process of this invention is more economical to construct and operate than are processes in which all components are subjected to the same isomerization conditions.

15 Accordingly, the process of this invention is claimed as:

1. A method for enhancing the octane number characteristics of an isomerizable feed stock containing substantial amounts of C_5 , C_6 , and C_7 saturated paraffinic hydrocarbons which comprises fractionating said feed stock to produce a low-boiling fraction containing n-pentane, and being substantially free from n-heptane, and a high-boiling fraction containing n-heptane and being substantially free from n-pentane, isomerizing said low-boiling fraction in the presence of a noble metal catalyst, consisting essentially of a metal selected from the group consisting of platinum and palladium on a suitable support, to produce a first reaction effluent, isomerizing said high-boiling fraction in the presence of a composite catalyst prepared by impregnating a refractory, acidic, mixed oxides base with a hydrogenation agent, and preconditioned by reduction, followed by oxidation at 650°-750° F., and reduction with hydrogen at 650°-750° F., to produce a second reaction effluent, the isomerizing of said first and second fractions being carried out under the following conditions:

	Low-Boiling Fraction	High-Boiling Fraction
Temperature, ° F.....	830-900	600-750
Pressure, p.s.i.g.....	200-500	180-1,000
Liquid Weight Hourly Space Velocity.....	2-10	0.1-2.0
H_2 /hydrocarbon mole ratio.....	0.1-0.5	0.1-4.5

65 fractionating the first and second reaction effluents in a product recovery system to recover a liquid product rich in branched-chain C_5 - C_7 paraffinic hydrocarbons and having enhanced performance characteristics.

70 2. A method for enhancing the octane number characteristics of an isomerizable, hydrocarbon feed stock containing substantial amounts of normal C_5 , C_6 , and C_7 saturated, paraffinic hydrocarbons which comprises fractionating said feed stock to produce a low-boiling fraction consisting essentially of n-pentane, and a high-boiling fraction containing n-hexane and n-heptane, isomerizing said low-boiling fraction in the presence of a noble metal catalyst, consisting essentially of a metal selected

from the group consisting of platinum and palladium on a suitable support, to produce a first reaction effluent, isomerizing said high-boiling fraction in the presence of a composite catalyst prepared by impregnating a refractory, acidic, mixed oxides base with a hydrogenation agent, and preconditioned by reduction, followed by oxidation at 650°-750° F., and reduction with hydrogen at 650°-750° F., to produce a second reaction effluent, the isomerizing of said first and second fractions being carried out under the following conditions:

	Low-Boiling Fraction	High-Boiling Fraction
Temperature, ° F.....	830-900	600-750
Pressure, p.s.i.g.....	200-500	180-1,000
Liquid Weight Hourly Space Velocity.....	2-10	0.1-2.0
H ₂ /hydrocarbon mole ratio.....	0.1-0.5	0.1-4.5

fractionating the first and second reaction effluents in a product recovery system to recover a liquid product rich in branched-chain C₅-C₇ paraffinic hydrocarbons and having enhanced performance characteristics.

3. A method for enhancing the octane number characteristics of an isomerizable, petroleum-derived feed stock containing substantial amounts of normal C₅, C₆ and C₇ saturated, paraffinic hydrocarbons which comprises fractionating said feed stock to produce a low-boiling fraction consisting essentially of n-pentane, and a high-boiling fraction containing n-hexane and n-heptane, isomerizing said low-boiling fraction in the presence of a noble metal catalyst, consisting essentially of a metal selected from the group consisting of platinum and palladium on a suitable support, to produce a first reaction effluent, isomerizing said high-boiling fraction in the presence of a composite catalyst prepared by impregnating a refractory, acidic, mixed oxides base with a hydrogenation agent, and preconditioned by reduction, followed by oxidation at 650°-750° F., and reduction with hydrogen at 650°-750° F., to produce a second reaction effluent, the isomerizing of said first and second fractions being carried out under the following conditions:

	Low-Boiling Fraction	High-Boiling Fraction
Temperature, ° F.....	830-900	600-750
Pressure, p.s.i.g.....	200-500	180-1,000
Liquid Weight Hourly Space Velocity.....	2-10	0.1-2.0
H ₂ /hydrocarbon mole ratio.....	0.1-0.5	0.1-4.5

fractionating the first and second reaction effluents in a product recovery system to recover a liquid product rich in branched-chain C₅-C₇ paraffinic hydrocarbons and having enhanced performance characteristics.

4. A process in accordance with claim 3 in which said noble metal catalyst is platinum and said preconditioned, composite, isomerization catalyst is NiMoO₄ supported on silica-alumina.

5. A method for enhancing the octane number characteristics of an isomerizable, petroleum-derived feed stock containing substantial amounts of normal C₅, C₆, and C₇ saturated, paraffinic hydrocarbons which comprises fractionating said feed stock to produce a low-boiling fraction consisting essentially of n-pentane, and a high-boiling fraction containing n-hexane and n-heptane, isomerizing said low-boiling fraction in the presence of a noble metal catalyst, consisting essentially of a metal selected from the group consisting of platinum and palladium on a suitable support, to produce a first reaction effluent, isomerizing said high-boiling fraction in the presence of a composite catalyst prepared by impregnating a refractory, acidic, mixed oxides base with a hydroge-

tion agent, and preconditioned by reduction, followed by oxidation at 650°-750° F., and reduction with hydrogen at 650°-750° F., to produce a second reaction effluent, the isomerizing of said first and second fractions being carried out under the following conditions:

	Low-Boiling Fraction	High-Boiling Fraction
10 Temperature, ° F.....	830-900	650-725
Pressure, p.s.i.g.....	350-500	350-750
Liquid Weight Hourly Space Velocity.....	2-5	0.5-1.5
H ₂ /hydrocarbon mole ratio.....	0.1-0.5	0.5-3.5

15 fractionating the first and second reaction effluents in a product recovery system to recover a liquid product rich in branched-chain C₅-C₇ paraffinic hydrocarbons and having enhanced performance characteristics.

20 6. A process in accordance with claim 5 in which said noble metal catalyst is platinum.

7. A process in accordance with claim 5 in which said preconditioned, composite isomerization catalyst is NiMoO₄ supported on silica-alumina.

25 8. A method for enhancing the octane number characteristics of an isomerizable petroleum-derived feed stock containing substantial amounts of normal C₅, C₆, and C₇ saturated, paraffinic hydrocarbons which comprises fractionating said feed stock to produce a low-boiling fraction, consisting essentially of n-pentane and a high-boiling fraction containing n-hexane and n-heptane, isomerizing said low-boiling fraction in the presence of a noble metal catalyst, consisting essentially of 0.1-1.0 weight percent of platinum supported on an alumina carrier, to produce a first reaction effluent, isomerizing said high-boiling fraction in the presence of a composite catalyst prepared by impregnating a silica-alumina carrier with 2-10% wt. of NiMoO₄, and preconditioned by reduction, followed by oxidation at 650°-750° F., and reduction with hydrogen at 650°-750° F., to produce a second reaction effluent, the isomerizing of said first and second fractions being carried out under the following conditions:

	Low-Boiling Fraction	High-Boiling Fraction
45 Temperature, ° F.....	850-875	650-725
Pressure, p.s.i.g.....	350-500	350-750
Liquid Weight Hourly Space Velocity.....	2-4	0.5-1.5
H ₂ /hydrocarbon mole ratio.....	0.1-0.5	0.5-3.5

55 fractionating the first and second reaction effluents in a product recovery system to recover a liquid product rich in branched-chain C₅-C₇ paraffinic hydrocarbons and having enhanced performance characteristics.

60 9. A method for enhancing the octane number characteristics of an isomerizable feed stock containing about 20 vol. percent C₅, 30 vol. percent C₆, 30 vol. percent C₇ saturated paraffinic hydrocarbons and 20 vol. naphthenes, which comprises fractionating said feed stock to produce a low boiling fraction containing n-pentane, and being substantially free from n-heptane, and a high-boiling fraction containing n-heptane and being substantially free from n-pentane, isomerizing said low-boiling fraction in the presence of a noble metal catalyst, consisting essentially of 0.5% by weight of platinum supported on an alumina carrier to produce a first reaction effluent, isomerizing said high-boiling fraction in the presence of a composite catalyst prepared by impregnating a silica-alumina carrier with 10% wt. of NiMoO₄, and preconditioned by reduction, followed by oxidation at 650°-750° F., and reduction with hydrogen at 650°-750° F., to produce a second reaction effluent, the isomerizing of said

first and second fractions being carried out under the following conditions:

	Low-Boiling Fraction	High-Boiling Fraction
Temperature, ° F.	830	660
Pressure, p.s.i.g.	500	350
Liquid Weight Hourly Space Velocity	2.5	1.0
H ₂ /hydrocarbon mole ratio	0.25	3

10

fractionating the first and second reaction effluents in a product recovery system to recover a liquid product rich

in branched-chain C₅-C₇ paraffinic hydrocarbons and having enhanced performance characteristics.
